UNITED STATES PATENT OFFICE

2,634,520

EARTH EXCAVATING TEETH FOR
BULLDOZER MOLDBOARDS

Clayton B. Foster, Maysville, Okla.

Application April 20, 1950, Serial No. 157,014

4 Claims. (Cl. 37—145)

1

The present invention relates to novel ways and means whereby a conventional type bulldozer blade or moldboard may be augmented and more successfully used in excavating and disintegrating relatively hard and stubborn earth formations, whereby to greatly increase the utility and efficiency of said blade as an earth mover.

More particularly, I provide a plurality of co-acting heavy duty disintegrator teeth which are readily applicable and removable, which are individually unique in construction and which have their upper ends removably latched but securely held in operative position on the corresponding upper end portion of the stated blade.

An over-all and, therefore, general object of the invention is to structurally, functionally and otherwise improve on so-called attachment teeth devised by others and, in so doing, to provide a digging and disintegrating assemblage in which manufacturers and users will find their expected needs fully met, contained and amply available.

Another object of the invention has to do with a heavy duty and reliable tooth which is equipped with simple and practical stabilizing means which is rigidly but releasably connectible with the usual scraper bar across the lower edge portion of the moldboard, said means being in the form of a shank bracing cleat which rests against the scraper and is provided with a horizontal V-shaped rib, the vertex of which is provided with saw-teeth which assume an angle corresponding to the angle of the tooth proper, whereby to appreciably augment the ripping and disintegrating properties of the latter.

What is more, novelty is predicated on an attachment type tooth embodying a vertical shank whose upper end is provided with a right-angled shaped clip which serves as a hanger and stabilizer and which, in addition, is provided with a vertical upstanding keeper flange whereby said upper end may be readily but securely latched in a successfully operable position. Then, too, a further phase of novelty has to do with a plurality of slotted lugs which are welded to the upper head or flange portion of the moldboard and which are longitudinally spaced to accommodate a heavy handle-equipped latching rod, said rod passing through the slots in the lugs and engaging the stated keeper flanges to hold the attaching clips or brackets in place, said rod constituting a gravity seated latch member and being withdrawable from the slotted lugs to facilitate application and removal of the several excavating and disintegrating teeth.

In the accompanying sheets of drawings where- 55 vanted. When it is desired to slip the rod out

2

in like numerals are employed to designate like parts throughout the views:

Fig. 1 is a perspective view of a bulldozer-blade or moldboard equipped with readily applicable and removable excavating and disintegrating teeth constructed in accordance with the principles of the present invention;

Fig. 2 is a fragmentary rear elevation of the right hand portion of the structure shown in Fig. 1;

Fig. 3 is a perspective view of the same end portion showing the upper corner only and showing the manner in which the handle is turned up for purposes of withdrawing the latching rod in the manner to be hereinafter described;

Fig. 4 is a vertical section on the line 4—4 of Fig. 1, looking in the direction of the arrows;

Fig. 5 is a perspective view of one of the tooth units per se; and,

Fig. 6 is a fragmentary top plan view with certain parts appearing in full lines in their normal position and corresponding parts appearing in phantom or broken lines in other positions.

Reference being had first to the old parts and referring in particular to Figs. 1 and 4, the earth-moving moldboard or so-called bulldozer blade is denoted by the numeral 8 and is of customary horizontally elongated concavo-convex form. The usual horizontal scraper blade 10 is bolted or otherwise secured as at 12 to the lower horizontal edge portion of the moldboard. The numerals 14 designate vertical end flanges and 15 denotes the horizontal top flange. The pusher beam is denoted at 16 and complementary diagonal braces by the numerals 17—17.

In carrying out the principles of the present invention, I provide a plurality of vertical longitudinally spaced lugs or ears 18 and these are welded to the flange 15 at longitudinally spaced points as best shown in Fig. 1. The lugs are provided with vertically elongated slots 20 which serve to accommodate an insertable and removable heavy latching rod 22. This rod is inserted through the slots and thus normally anchored in the lugs. However, it may be withdrawn from the lugs as shown in dotted lines in Fig. 6. It is provided at one end with a washer 24 and cotter key 26 (see Fig. 1) and at the opposite end it is provided with a lateral handle 28. This handle is normally swung down and held in a retainer notch 30 formed at one end of the flange 15 (see Figs. 2 and 3, respectively). In Fig. 2, the handle is shown dropped down into the notch and thus endwise displacement of the latching rod is pre-

to the dotted line position shown in Fig. 3 the latch handle is swung up from the retaining notch to the position shown in Fig. 3.

It will be noticed in connection with the means just described that by removing the cotter key 26 and taking off the washer 24 (Fig. 1) the latching rod 22 is thus free to be slid through the slots in the various lugs 18, that is, from right to left as shown in dotted lines in Fig. 6. Not only this, the cross-section or diameter of the rod is considerably less than the vertical lengths of the slots 20 in the lugs. This arrangement is to allow clearance and play of the rod in the slots. As a matter of fact, it is possible to bodily lift the rod in the slots in the several lugs sufficiently high to facilitate the insertion and removal of the excavating and disintegrating tooth units 32. Normally, however, it is preferred to completely withdraw the rod from the slotted lugs to permit all of the units to be readily applied and removed. There are instances, however, when it is desired to merely temporarily take off one unit and as stated, this can actually be done without completely slipping the rod out of the lugs. Another way is to simply remove the cotter key 26 and washer 24 and partly slip the rod through the first two lugs at the left in Fig. 1 and thus clear the way for applying or removing a single tooth unit at this end of the moldboard only.

Taking up the construction now of the various units 32, they are all the same in construction and a description of one will suffice for all. Referring to Fig. 5, the beveled tooth or prong is denoted by the numeral 34 and this is at an obtuse angle with respect to the rectangular heavy duty shank 36. The adapter clip or bracket for attaching and hanging the units 32 is denoted by the numeral 38 and this is of general right angular form and includes a depending vertical flange 40 which is welded to the upper end of the shank 36 and is at right angles thereto. Then, there is a shelf-like intermediate hanger flange 42 which rests on the aforementioned moldboard flange 15, the latter flange then serving as a sort of a ledge. The remaining or third flange 44 is also vertical and this is a keeper flange. Therefore, when the two flanges 42 and 44 are in place, the flange 44 rises between the adjacent pairs of lugs 18-18. It is of a height at least equal to the length of the slots in said lugs. It follows, therefore, that with the brackets 38 in place and the rod 22 located in the slotted lugs, the rod forms a latch for holding all of the several units 32 on the upper portion or flange 15 of the moldboard. Attached to the lower end of the shank 36 is a hold down stabilizer cleat 46 and this comprises an open frame 48 which is welded to the shank and which has a horizontal plate-like portion 50 on its bottom. One edge of this plate is beveled and of general V-shaped form and provides a rib with saw-teeth 51. This rib is in the same plane as the tooth 34. The opposite edge of the plate portion if formed into an anchoring lip or flange 52 which is at the correct angle to engage the cutting edge of the scraper blade 10 as best shown in Fig. 4. The frame 48 is at approximate right angles to the longitudinal axis of the shank 36, as illustrated. Thus a substantial support is had for balancing and stabilizing the attachable lower end portion of the units 32 to the blade 10.

Reference being had to Fig. 1, the complete assemblage, ready for use, is fully illustrated. As shown here, a stabilizing cleat 46 serves to

anchor and attach the toothed lower end of each unit 32. On the other hand, the right angle adapter clips or brackets 38 serve to hang and suspend the upper ends of the shanks on the ledge flange 15 of the moldboard. The latching rod 22 seated in the slots in the various lugs 18 and with the handle 28 "down" in the retainer notch 30, as shown in Fig. 2, said rod serves to latch and releasably hold the various adapter brackets in place.

A moldboard and bulldozer blade constructed with these various attachments latched in place thereon has its capacity and utility greatly enhanced. Experiments have shown that these excavating and disintegrating teeth units when applied as shown will enable a bulldozer to perform unexpectedly new results. In fact, the teeth will dig into rigid packed road surfaces, into shale and actually into coal. They perform work for digging and disintegrating solid masses short of solid rock formations.

It is believed that the mode of applying and removing the attachments will be clear from the description and drawings.

25. It is thought that persons skilled in the art to which the invention relates will be able to obtain a clear understanding of the invention after considering the description in connection with the drawings. Therefore, a more lengthy description is regarded as unnecessary.

30. Minor changes in the shape, size and arrangement of details coming within the field of invention claimed may be resorted to in actual practice, if desired.

35. Having described the invention, what is claimed as new is:

1. An attachment for a bulldozer moldboard comprising a linearly straight shank having an angularly disposed tooth at its lower end, a rectangular hold-down and stabilizing frame integral with said shank at the juncture of the latter and said tooth, said frame having a forwardly projecting bevelled toothed rib on its lower edge portion in alignment with the junctural connection between said shank and tooth, and having a tooth anchoring flange also on its lower edge portion and facing rearwardly, and clip means on the upper end of said shank whereby latter may be attached to and hung from a co-acting upper portion of said moldboard, said clip means embodying a keeper flange.

2. In a structural assemblage of the class shown and described, a bulldozer moldboard 55 provided along its top portion with a horizontal ledge flange, said flange being provided at one end with a retainer notch, a plurality of vertically disposed lugs rigidly secured on and rising above said flange, said lugs having vertically elongated slots, a relatively heavy latch rod 60 fitted removably in the slot in said lugs, said rod paralleling said ledge flange and having a handle at one end normally seated in said retainer notch the lengths of said slots being greater than the cross section of said rod, and a plurality of excavating units provided on their upper ends with right angularly shaped adapter clips suspended on said ledge flange, said clips having upstanding keeper flanges releasably engaged with and held in place by said rod.

3. An attachment for a bulldozer moldboard comprising a linearly straight rigid shank having an obtuse-angled tooth at its lower end, a clip embodying a depending abutment flange secured intermediate its ends to the upper end of said

shank and disposed at right angles to the axis of the shank, having a vertical upstanding keeper flange on a plane above the upper end of said shank and having an intervening horizontal flange between the abutment flange and keeper flange, a rectangular frame constituting a cleat and secured to the shank adjacent to the upper end of said tooth, said frame having a forwardly projecting bevelled rib and said rib being serrated and providing teeth and having, in addition, a rearwardly projecting anchoring flange adapted to engage with a lower edge portion of said moldboard.

4. In a structural assemblage of the class described, a bulldozer moldboard provided along its top portion with a horizontal ledge flange, a vertically elongated lug rigidly secured to and rising above the plane of said flange, said lug having a vertically elongated rod accommodating slot therein, an excavating unit comprising a shank having a tooth at its lower end, having toothed cleat means at said lower end provided with complementary means for releasably engag-

5 ing an edge portion of said moldboard, a clip rigidly secured to the upper end of said shank and having a horizontal flange resting on said ledge flange and provided, in addition, with a vertically extending keeper flange in alignment with said lug and offset to one side of the vertical dimension of said slot, and a latch rod adjustably and removably mounted in the slot in said lug, said latch rod being cylindrical in cross section and of a cross section less than the length of the slot and being engageable with said keeper flange.
